SUSPENDERS

Haskel S. Frank, Chicago, Ill., assignor to A. Stein & Company, Chicago, Ill., a corporation of Illinois

Application July 30, 1934, Serial No. 737,517

2 Claims. (Cl. 241—12)

This invention relates to suspenders such as are worn by men for supporting trousers.

The main objects of the invention are to provide a suspender construction which will permit the various portions of the suspenders to maintain a normally flat condition when worn, regardless of the spreading or angular relationship of the various strap portions of the suspenders; to provide a suspender construction which will afford a greater degree of comfort than is offered by conventional constructions; to provide a suspender structure having the features indicated and which may be produced economically and sold at a low price; and to provide an improved suspender construction which will be light in weight, cool to wear and durable.

Other objects and advantages of the invention will be understood by reference to the following specification and accompanying drawing, in which there is illustrated a pair of suspenders embodying a selected form of the invention.

In the drawing—

Fig. 1 is a perspective illustrating a pair of the improved suspenders approximately in the form in which they are worn;

Fig. 2 is an enlarged illustration of a portion of the suspenders and corresponding to a portion of Fig. 1; and

Fig. 3 is a section on the line 3—3 of Fig. 1.

Referring now to the drawing, the improved suspenders include shoulder straps 5 and 6 respectively, which are provided at their front ends with trousers-engaging tabs 7, 7. The tabs 7, 7 may be of any suitable material, for example, leather, and they may be connected to the shoulder straps 5 and 6 in any convenient manner. Where the shoulder straps 5 and 6 are formed of elastic webbing, as herein contemplated, the tabs may be secured to the respective straps through the agency of metal buckles 8, 8 in a more or less conventional manner. Devices indicated at 9, 9 constitute adjusting clasps for adjusting the effective length of the suspenders.

Back straps 10 and 11 are also provided and these are preferably formed of the same kind of material as the shoulder straps 5 and 6. The lower ends of the back straps 10 and 11 may be provided with trousers-engaging tabs 12, 12 of leather or other suitable material.

The shoulder straps and back straps are connected together through the agency of a connecting member 13, which is elongated and extends transversely of the length of the straps. Adjacent its opposite ends, the member 13 is provided with circular openings 14, 14 which result in the

formation, in effect, of curved arms 15, 15 adjacent the ends of the connecting member 13. The member 13 is preferably formed of flexible material such as leather. Material such as exemplified by leather retains its flexibility in the completed suspenders and hence adds materially to the comfort of the suspenders when worn.

For connecting the back ends 16, 16 of the shoulder straps 5 and 6 and the upper ends 17, 17 of the back straps 10 and 11 to the connecting member 13, anchoring elements 18 of leather or other suitable material are provided. As shown most clearly in Fig. 3, the anchoring elements 18 are extended through the openings 14 of the connecting member 13 and looped around the curved arm portions thereof and the opposite ends of each of the elements 18 caused to embrace the end portion of one of the straps 5, 6, 10 and 11. The elements 18 are anchored to the respective straps by being stitched thereto, as indicated at 19.

The connecting member 13 and the anchoring elements 18, 18 are preferably formed of leather or other pieces, all of which are cut by the same die so as to be of like size and shape. The elements 18 are not, of course, apertured adjacent their ends as is the member 13, and the punching of the apertures 14 may be effected by an independent operation. It will be observed that the members 13 and elements 18 are each reduced in width approximately midway their lengths so that the median portions of the members 18 which are located within the openings 14, will pass freely therethrough so that said elements may slide around the curved arm portions with comparative ease.

The straps 5, 6, 10 and 11 are, by the described construction, independently adjustable relative to each other so that they are adapted to lie flat when worn, regardless of the spreading of the respective parts. It will be understood that on a very wide shouldered and heavy-set person, the shoulder straps 5 and 6 and the back straps 10 and 11 will normally diverge at a considerably greater angle than is the case when the suspenders are worn by a slender person. By reason of the adjustable structure described, the respective straps need not be stretched or otherwise distorted to fit different types of men, but are, in effect, self-adjusting to proper fitting condition so that the straps may lie flat without buckling or bulging at any point and without excessive stretching in any localized area. A high degree of comfort results from the adaptability of the suspenders to different sizes, as above indicated.

Economy of construction is facilitated by reason of the use of like sized and shaped members in producing the connecting member 13 and elements 18. As indicated in Fig. 3, the member 13 is of two-ply construction. The two plies need not be united and they may be replaced by a single-ply element if desired. However, in the practical production of pieces like the connector 13 and the elements 18, of leather, leather which is finished on one face and unfinished on the other face, is preferably used for economic reasons. By making the member 13 two-ply, the unfinished faces of two such members are placed together so that the outside surfaces of the two-ply element are finished. Thus no heavy or expensive material finish on both faces need be handled.

The straps 5, 6, 10 and 11 may, of course, be formed of material other than elastic webbing and other changes may be made without departing from the spirit of the invention, the scope of which should be determined by reference to the following claims, the same being construed as broadly as possible consistent with the state of the art.

25 I claim:

1. Suspenders comprising shoulder straps having their front ends provided with trousers-engaging elements, a pair of back straps having their lower ends provided with trousers-engaging elements, elongated, flexible sheet material means extending transversely of said straps and provided adjacent its ends with curved arm portions, and flexible sheet material elements looped around said curved arm portions and respectively secured to the upper and back ends respectively

of said back and shoulder straps, whereby said back and shoulder straps are adjustable relative to each other and adapted to lie flat when worn in various positions of adjustment.

2. Suspenders comprising a pair of shoulder straps, a pair of back straps, and a connector to which said shoulder and back straps are connected independently of each other, said connector being formed of flexible sheet material and having a pair of openings spaced transversely of the length of the suspenders, said openings being of smaller diameter than the width of said straps, the connections between said shoulder and back strap ends and said connector each comprising a flexible sheet material element having outer end portions of substantially the same width as the respective straps and a narrow intermediate portion, each element being projected through one of the openings in the connector and folded upon itself so as to cause said narrow intermediate portion to embrace a connector portion around such opening, said element being capable of being assembled with the connector as an incident to the inherent distortability of the flexible material of which said parts are formed, the overlapping portions of said folded element being disposed on opposite sides of the strap end with which the element is associated and fixedly united thereto by stitching, one shoulder strap and one back strap having its end element associated with one of said openings and the other shoulder strap and back strap being associated with the other of said openings.
